UNITED STATES PATENT OFFICE.

CECIL H. BOYULS, OF LOUISVILLE, KENTUCKY.

GARMENT-FORMER.

1,392,907.

Specification of Letters Patent. Patented Oct. 11, 1921.

Application filed March 5, 1921. Serial No. 450,045.

To all whom it may concern:

Be it known that I, CECIL H. BOYULS, a citizen of the United States of America, residing at Louisville, in the county of Jefferson and State of Kentucky, have invented 5 certain new and useful Improvements in Garment-Formers, of which the following is a specification.

This invention relates to garment formers 10 and has special reference to a garment former for shirt bodies.

One important object of the invention is to improve the general construction of devices of this character.

15 A second object of the invention is to provide a novel and improved machine of this class having expansion sides for stretching the shirt to be ironed.

A third important object of the invention 20 is to provide an improved machine of this class having novel operating means for controlling the expansion elements.

A fourth important object of the invention 25 is to provide an improved tail straightening and clamping mechanism in such devices.

With the above and other objects in view, 30 as will be hereinafter apparent, the invention consists in general of certain novel devices of construction and combinations of parts hereinafter fully described, illustrated in the accompanying drawings and specifically claimed.

In the accompanying drawings like characters of reference indicate like parts in the several views, and:—

Figure 1 is a front elevation of the improved ironing machine.

Fig. 2 is a side elevation thereof.

40 Fig. 3 is a face view of the device removed from its standard and having the top or ironing surface broken away to show the working parts.

Fig. 4 is a bottom view with the cover plates over the working parts broken away.

Fig. 5 is an elevation showing the front end of the device.

Fig. 6 is a similar elevation of the rear end of the device.

50 Fig. 7 is a section on the line A—A of Fig. 5.

Fig. 8 is an enlarged scale section of the line B—B of Fig. 7.

In the embodiment of the invention herein

disclosed there is provided a base 10 from 55 which rises a standard 11, T-shaped in cross section and having its upper end curved forwardly. On this forwardly inclined portion the head of the T is expanded laterally to provide a main supporting plate 12. Mounted on this plate 12 is a hollow body member 13 having inlet and outlet pipes 14 and 15 respectively, said pipes being for the purpose of conveying steam to and exhausting it from the body in the manner usual in devices of this character. The base 16 of this body fits against the plate 12 and is provided with an opening 17 leading to a channel 18 formed longitudinally of said body in its upper surface and continuing in a somewhat 70 shallower channel 19 likewise formed in the upper surface of the body. On the front of the plate 12 is formed a boss 20 which is aligned with the opening 17 and is provided with an opening 21 which extends also 75 through the plate 12 to form a continuation of said opening 17. Through this opening and into the channel 18 extends a screw bar 22 carrying on its outer end a nut 23 provided with a hand wheel 24. This nut is 80 held from longitudinal movement by a finger plate 25 secured to the top of the standard and projecting into a groove 26 formed on said nut.

To the rear end of the screw bar 22 is 85 connected the forward end of a rack bar 27 meshing with the gears 28 held in pockets 29 in the face of the body 13. These gears are fixed on shafts 30 which extend through the body into transverse slots 31, the ends projecting into these slots carrying gears 32. Each of these gears 32 meshes with a pair of wing bars 33, the bars of each pair being located on opposite sides of the respective gear and moving in the grooves or slots 31. 90

Thus rotation of the hand-wheel in one direction moves the bars 33 outwardly and rotation of said hand wheel in the opposite direction moves the bars inwardly. At each side of the body is a wing member 34 which is carried on the outer ends of the bars 33 projecting on that side so that the action of the hand wheel as above described collapses these wings on the body or expands them away from 105 said body. The body is suitably recessed or rabbeted to accommodate these wings which, when collapsed fit closely to

2
said body and are heated by contact therewith. For the better preservation, or rather storage, of heat the body and wings are made of metal of considerable thickness so 5 that, once these parts are heated, they will retain the heat for a sufficient time to permit effective working of the device. Attached to the edges of these wing members are thin telescopically arranged cover plates 10 35 which extend over the body and working mechanism so as to prevent the garments coming in contact therewith.

Projecting from each of the wing members 34 adjacent the front end thereof is a bracket 36 carrying a pair of rods 37 and 38. On these rods is slidably mounted a carriage 39. On that part of the carriage sliding on the rod 38 is a rotatable sleeve 40 having a handle 41 on one side and a curved arm 20 42 on the other side, a presser plate 43 being attached to the free end of said arm to engage against the under side of the machine and hold the tails of the garment. A spring 44 connects said arm and that part 25 of the carriage which slides on the rod 37 thus urging the presser plate against the under side of the main part of the device.

In operation the clamps are moved up on their rods and the handles moved inward to 30 open the clamps. A shirt, which has been previously dampened and which has its collar band buttoned, is then placed on the form, covering the same. The clamps, which have been held open by suitable catches (not 35 shown) are now released and the rear tails of the garment gripped by the presser plates against the plates 35, the front tails being held by spring clamps 45 of any desired construction. The operator now manipulates 40 the hand wheel to expand the wings and stretch the garment tightly over the machine. The handles 41 are then pulled forward to smooth down the tails. After the garment has been left in this position the 45 necessary time the clamps are released and the form collapsed. The garment is then removed leaving the machine ready for a second garment. It is obvious that this form may be used in place of the form shown in 50 my Patent Number 1,357,218, November 2, 1920.

It is obvious that minor changes may be made in the form and construction of the invention without departing from the material principles thereof. It is not, therefore, desired to confine the invention to the exact form herein shown and described but it is wished to include all such as properly come within the scope claimed.

Having thus described the invention, 60 what is claimed as new, is:

1. In a garment former, a body portion, wings at the sides of the body portion, means to move said wings toward and from the body sides, and tail clamps carried by 65 and movable with the wings.

2. In a garment former, a body portion, wings at the sides of the body portion, means to move said wings toward and from the body sides, and tail clamps slidably mounted 70 on the wings for movement longitudinally of said wings.

3. In a garment former, a body portion, wings at the sides of the body portion, means to move said wings toward and from 75 the body sides, tail clamps slidably and rockably mounted on said wings for movement longitudinally of the wings and including presser plates for engaging the garment tails and smoothing them into position. 80

4. In a garment former, a hollow body, laterally disposed wings at the sides of said body and conforming in shape thereto, plates carried by the wings and extending across 85 the body in overlapping arrangement, and means to expand and collapse the wings.

5. In a garment former, a hollow body, laterally disposed wings at the sides of the body and conforming thereto, plates above 90 and below said body having their outer edges fixed to the wings and their inner portions extending in overlapping relation across said body, and means to expand and collapse the wings. 95

6. In a garment former, a body, wings disposed at the sides of said body, a rack bar movable longitudinally of the body, wing supporting rack bars movable transversely of the body and carrying the wings on their 100 outer ends, gearing connecting the longitudinally movable and the transversely movable rack bars, and means to move the first mentioned rack bar.

7. In a garment former, a body, wings disposed at the sides of said body, a rack bar movable longitudinally of the body, wing supporting rack bars movable transversely of the body and carrying the wings on their outer ends, gearing connecting the longitudinally movable and the transversely movable rack bars, means to move the first mentioned rack bar, and plates carried by the wings and extending over the body in overlapping relation to cover said rack bars and gearing. 105 110 115

In testimony whereof I affix my signature.
CECIL H. BOYULS.
